UNITED STATES PATENT OFFICE.

ROTHESAY P. KIDDER, OF LOWELL, MASSACHUSETTS, ASSIGNOR, BY MESNE ASSIGNMENTS, TO EDEN WASHER CORPORATION, A CORPORATION OF DELAWARE.

QUICK-RELEASE WRINGER MECHANISM.

Application filed April 19, 1920. Serial No. 374,852.

To all whom it may concern:

Be it known that I, ROTHESAY P. KIDDER, a citizen of the United States, and a resident of the city of Lowell, in the county of 5 Middlesex and State of Massachusetts, have invented certain new and useful Improvements in a Quick-Release Wringer Mechanism; and I do hereby declare that the following is a full, clear, and exact description 10 of the same, reference being had to the accompanying drawings, and to the numerals of reference marked thereon, which form a part of this specification.

This invention relates to an improved 15 type of wringer wherein the wringer rolls are provided with a quick release mechanism to permit a substantially instantaneous separation of the wringer rolls.

It is an object of this invention to provide 20 a balanced pressure wringer with means whereby the wringer rolls may be instantaneously released.

A further object of the invention is the construction of a wringer wherein the rolls 25 are adapted to be adjusted by means of a single adjusting screw and a spring.

It is furthermore an object of this invention to provide a clothes wringer with a roll 30 releasing mechanism of a simple and effective construction to permit instantaneous release of the wringer rolls to remove the pressure from clothes passing between the rolls.

Other and further important objects of 35 this invention will be apparent from the disclosures in the drawings and specification.

The invention (in a preferred form) is 40 illustrated in the drawings and hereinafter more fully described.

On the drawings—

Fig. 1 is an enlarged fragmentary longitudinal section of a wringer embodying the principles of this invention showing parts 45 in elevation and parts broken away.

Fig. 2 is a section taken on line 2—2 of Fig. 1.

Fig. 3 is a transverse detail section taken on line 3—3 of Fig. 1.

Fig. 4 is a detail sectional view taken on line 4—4 of Fig. 3.

Fig. 5 is a section taken on line 5—5 of Fig. 3 with parts in elevation and showing the operation of the adjusting screw in 55 dotted lines.

As shown on the drawings—

The reference numeral 1 indicates a wringer frame having a removable hood or top 2 adapted to close the upper chambered portion of the frame. Latches 3 and tie rods 4 are provided for holding the hood 2 in place.

Secured in the lower portion of the frame 1 by bolts 5 is a drain trough 6 to one end of which is connected a drain pipe or spout 65 7. The drain trough 6 is positioned below wringer rolls 8 which are provided with axial shafts or spindles 9 the ends of which project into vertical guide slots 10 formed in partition plates 11.

Mounted in each end of the frame 1 are a pair of oppositely disposed bearing guides 12 between which lower and upper spindle bearing blocks 13 and 14 respectively are placed. Roll guards 15 are provided to protect the ends of the rolls. Disposed longitudinally in the wringer frame above the upper roll 8 is a convex or upwardly curved wringer plate spring 16 provided at its middle or highest portion with a socket 17 for 80 removably receiving the lower end of an adjusting device or screw 18. The screw 18 projects upwardly through a longitudinal slot 19 provided in the top wall of the hood 2. A hand wheel 20 is secured on the upper projecting end of the adjusting screw 18 to facilitate operation thereof.

The ends of the plate spring 16 seat in notches provided in the upper bearing blocks 14 as shown in Fig. 1. Plates 21 90 are secured in the top of the upper bearing blocks 14 for the purpose of retaining the ends of the spring 16 in place. Rigidly secured to the middle portion of the inner surface of the sides of the frame hood 2 are 95 a pair of oppositely disposed release brackets 22, having link pins 23 secured thereto. The pins 23 project into slots 24 provided in links 25 mounted adjacent the release brackets 22. Holes are provided near the lower ends of the links 25 for receiving the trunnions 26 of a knuckle or block 27. The block 27 separates the links 25 and is provided with a threaded passage through which the screw 18 is threaded. The upper 100 ends of the links 25 contact the inner surface of the top wall of the frame hood 2.

The operation is as follows:

The wringer rolls 8 have the spindles 9 thereof journaled in the bearing blocks 13 110

and 14. The plate spring 16 which engages in the notches of the upper bearing blocks 14 is adapted to be stressed or depressed by turning the single adjusting screw 18 by means of the hand wheel 20. The screw 18 threads downwardly through the block 27 and the inner end of said screw being normally engaged in the spring socket 17 acts to compress or force the spring downwardly. The upper bearing blocks 14 are thus moved downwardly between the guide members 12, thereby moving the upper roll 8 toward the lower roll, an amount depending upon the adjustment of the adjusting screw 18.

When the wringer is operated, wet clothes may be run between the wringer rolls 8 for wringing the greater part of the water from the wet clothes. The water removed from the clothes falls into the trough 6 and is permitted to be drained off through the drain spout 7.

In case of injury or jamming of the rolls, the upper wringer roll can be quickly released from the lower wringer roll by longitudinally swinging the screw 18 to one side or the other. During the swinging of the screw 18, the block 27 will rotate on its trunnions 26, since the links 25 are tightly pressed against the top of the casing and cannot swing until the lower end of the screw has been swung out of the socket in the spring plate 16. As soon as the end of the screw 18 has been shifted out of said socket, the links 25 will drop sufficiently on account of their lost motion connection with the rigidly secured brackets 22 so that the block 27 can be laterally shifted with respect to an axis defined by the pins 23. Thus the links 25 that support the block 27 may be termed suspension members and the links 25 together with the block 27 form a stirrup that has lost motion connections with the rigid brackets 22, which stirrup will drop downwardly and swing laterally when the lower end of the screw is shifted out of its socket in spring plate 16.

I am aware that numerous details of construction may be varied through a wide range without departing from the principles of this invention, and I therefore do not purpose limiting the patent granted otherwise than necessitated by the prior art.

I claim as my invention:

55 1. A wringer comprising a frame having a slot in the top thereof, lower and upper bearing blocks in said frame, rolls in said frame engaged with said bearing blocks, a spring above said rolls having the ends thereof resting in said upper bearing blocks,

a socket formed in said spring, brackets secured in said frame on opposite sides of said spring, pins mounted on said brackets, slotted apertured links engaged on said pins, a block having a threaded passage therein, trunnions on said block pivotally engaged in the apertures of said links, and an adjusting screw projecting through the frame slot and threaded through the threaded passage of said block to engage in said 65 spring socket and depress said spring to cause adjustment of said rolls, said screw adapted to be swung in said frame slot to cause the inner end of said screw to leave the spring socket and thereby instantaneously release said spring and said rolls. 75

2. In a wringer having a pair of rolls with one movably mounted relative to the other, a spring plate co-acting with the ends of said movable roll, a stirrup, means for pivotally supporting said stirrup over the middle of said plate, and an adjustable device carried by said stirrup and co-acting with said spring plate for varying the tension of said spring plate. 85

3. In a wringer having a pair of rolls with one movably mounted relative to the other, a spring plate co-acting with the upper roll, a stirrup having a rotatable bearing mounted in the lower end thereof, means for supporting said stirrup over the middle portion of said spring plate, and an adjustable device supported by said rotatable bearing and co-acting with said spring plate for varying the pressure of 95 said plate on said rolls. 95

4. In a wringer having a pair of rolls mounted for relative movement, a spring plate bearing upon the ends of one of said rolls, a pair of supporting brackets above 100 the upper roll, suspension members pivotally connected to said brackets, a block rotatably supported by said members, and an adjusting screw extending through said block and in contact with said spring plate. 105

5. In a wringer having a pair of rolls mounted for relative movement in a vertical plane, a spring plate bearing upon the ends of one of said rolls, a stirrup supported for vertical and oscillatable movement, 110 and an adjustable device carried by said stirrup for varying the tension of said spring plate and effecting a quick release of one of said rolls.

In testimony whereof I have hereunto 115 subscribed my name in the presence of a subscribing witness.

ROTHESAY P. KIDDER.

Witness:

F. W. WILLARD.
